CLAIM

The ornamental design for lever for hospital bed, as shown and described.

DESCRIPTION

FIG. 1 is a left side elevational view of a lever for hospital bed showing my new design;

FIG. 2 is a front elevational view thereof;

FIG. 3 is a right side elevational view thereof;

FIG. 4 is a rear view elevational thereof;

FIG. 5 is a top plan view thereof;

FIG. 6 is a bottom view thereof;

FIG. 7 is an asymmetric view thereof;

FIG. 8 is a left side view of the second embodiment of a lever for hospital bed showing my new design;

FIG. 9 is a front elevational view thereof;

FIG. 10 is a right side view elevational view thereof;

FIG. 11 is a rear elevational view thereof;

FIG. 12 is a top plan view thereof;

FIG. 13 is a bottom view thereof; and,

FIG. 14 is an asymmetric view thereof.
